Attorney

UNITED STATES PATENT OFFICE.

ERNEST J. COLBOURN, OF SHELBYINA, MISSOURI.

RESTRAINING DEVICE.

1,229,717.

Specification of Letters Patent. Patented June 12, 1917.

Application filed March 28, 1916. Serial No. 87,286.

To all whom it may concern:

Be it known that I, ERNEST J. COLBOURN, a citizen of the United States, and a resident of the city of Shelbyina, in the county of 5 Shelby and State of Missouri, have invented certain new and useful Improvements in Restraining Devices, of which the following is a specification.

My invention relates to restraining devices and more particularly to that class 10 known as hopples.

The primary object of the present invention is to provide a hopple particularly adapted to cows, but may be applied to other 15 four-footed animals.

A second object of this invention is to provide a hopple that will effectively and securely prevent the animal from kicking.

Another important object of my invention 20 is to construct a hopple consisting of a one-piece harness and a shackle arrangement carried thereby that may be quickly applied to the animal.

Another object of the invention is to provide 25 a one-piece harness adapted to be applied to an animal and a shackle arrangement carried thereby that may be adjusted for animals of different heights.

A further object of my invention is to 30 provide an appliance of the above mentioned character which consists of few parts, is inexpensive to manufacture and which may be placed on the market at a comparatively low cost.

The above and other objects and advantages 35 of my improvements will fully appear from the following description taken in connection with the accompanying drawing and be explicitly defined in the appended 40 claims.

In the drawings,

Figure 1 shows my improved hopple applied to an animal.

Fig. 2 shows a modification of my improved 45 hopple also applied to an animal.

Fig. 3 is a detail view of the shackle arrangement.

Like reference characters indicate like parts in all the views.

50 Referring to the drawings, the numeral 10 indicates a forward body encircling strap or band having alined openings 11 at both ends thereof. 12 indicates a rear body en-

circling strap or band also having alined openings 13 at both ends. 55

Secured to the body strap 12, as at 14, is a strap 15 which extends at right angles thereto and carries a buckle 16 or other connecting device. Secured to the body strap 10, as at 17, is a strap 18 having openings 60 adapted for engagement with the buckle 16. These straps 15 and 18 make up what I term the back strap.

19 and 20 indicate short connecting straps having buckles or other connecting devices 65 21 and 22 secured to their upper ends. These buckles are adapted for engagement with the body straps 10 and 12.

The lower ends of the straps 19 and 20 are provided with loops 23 and 24. Loops 25 70 and 26 are also arranged upon the members 19 and 20 to receive the free ends of the body straps 10 and 12.

Loosely engaged in the loops 23 and 24 are the rings 27. Also loosely engaged with 75 the ring 27 are the diverging connections or straps 29 and 30. Relatively large rings 33 and 34, 35 and 36 are loosely engaged with the lower ends of the members 29 and 30. Horizontally disposed straps 37 and 38 are 80 loosely connected with the rings 33 and 34, 35 and 36. While I have described the diverging members and the horizontal members as straps, they may be chains or other flexible elements. 85

Engaged in the rings 33 and 34, 35 and 36 are chains or other flexible elements 39 and 40. These chains 40 carry snap hooks 41 and 42 upon their ends adapted to engage one of the links of the chains 39. A snap 90 hook 43 is carried by the ring 36. It will be noted that should it be desired to adjust the chains 39 and 40 carried by the rings 35 and 36, to the limbs of a smaller or large animal without disengaging the chains, the 95 snap hook 43 is simply engaged in any one of the links of these chains.

The elements carried by these straps 19 and 20 make up the shackle or locking device for the animal's limbs. 100

Should it be desired to adjust the shackle or locking device vertically for animals of differing heights, the buckles 21 and 22 are disengaged from the ends of the members 10 and 12 and adjusted up or down as the 105 case may be.

In applying my hopple to the animal, the forward body strap 10 is placed upon the animal's back just in front of its hips and the rear body strap 12 is also placed upon 5 the animal's back and in alinement with its limbs. The snap hooks 41 and 42 are now engaged with the chains 39.

In Fig. 2, a slightly modified form of the invention is shown. In this form, only one 10 body strap or band and only one short buckle carrying strap for each set of diverging straps 29 and 30 is employed.

This hopple is applied in the same manner as the first mentioned hopple, the body 15 strap being placed in front of the animal's hips and the flexible elements being then engaged around the animal's limbs.

From the foregoing description taken in connection with the accompanying drawings, 20 the advantages of the construction and the manner of application will be readily understood by those skilled in the art to which the invention appertains, and while I have described the method of application, 25 together with the forms which I now consider to be the best embodiment thereof, I desire to have it understood that the forms shown are only illustrative and that such changes may be made when desired as fall 30 within the scope of the appended claims.

Having described my invention what I

believe to be new and desire to secure and protect by Letters Patent of the United States, is:

1. In a hopple, a harness adapted to be 35 applied and mounted on the rear limbs of an animal, a plurality of diverging members connected to the lower ends thereof, and a chain joining and closely connecting the diverging members whereby the animal 40 is prevented from moving either of its rear limbs.

2. In a hopple, a harness comprising front and rear body straps, said harness adapted to be applied and mounted on the rear limbs 45 of an animal, a plurality of diverging members connected to the lower ends thereof, and a chain joining and closely connecting the diverging members to encircle the rear limbs of an animal to prevent one limb being 50 moved independently of the other.

3. In a hopple, a harness comprising forward and rear body straps, said harness adapted to be applied and mounted on the rear limbs of an animal, a short strap adjustably connected with each end of each of 55 the body straps, a shackle mechanism carried by the last named straps to encircle the rear limbs of an animal whereby one limb is prevented from moving independently of 60 the other.

ERNEST J. COLBOURN.
